UNITED STATES PATENT OFFICE.

RICHARD J. GREVSTAD, OF OLALLA, WASHINGTON.

HEATER.

Application filed March 22, 1926. Serial No. 96,448.

This invention relates to air-heating apparatus for use, more particularly, with brooders and the like.

The object of my invention is to provide an apparatus of this character which will be of inexpensive construction, efficient in use, and convenient to control.

More specific objects and advantages of the invention will appear in the following description.

The invention consists in the novel construction, adaptation and combination of parts hereinafter described and claimed.

In the accompanying drawing, Figure 1 is a transverse vertical section of an air-heating device embodying the present invention, said section being taken substantially on line 1—1 of Fig. 2; and Fig. 2 is a horizontal section on line 2—2 of Fig. 1.

In said drawing, the reference numeral 5 indicates a casing containing two compartments 6 and 7 disposed one above the other.

The lower compartment 6, which serves as a heating chamber, is open at the bottom and is provided with an imperforate peripheral wall 8 and a top wall or ceiling 9 having a central aperture 13.

The upper compartment 7, which serves as a hot-air reservoir, is provided with an imperforate peripheral wall 10, and a floor 11 and a top wall 12, each having a central aperture. Communication is had between the top of the heating chamber 6 and the hot-air reservoir 7 through a passage afforded by said aperture 13; and an outlet 14 is provided through the aperture in the top wall 12 of said reservoir for the delivery of hot air from the latter as, for example, into a service pipe 15.

This service pipe is extended to the brooder or other place which is to be heated and should be provided in proximity of its outlet with a damper of known or suitable construction which is not shown in the drawing.

As illustrated, the walls 9 and 11 of the respective compartments are joined together about the periphery of the passage 13, such walls being formed, preferably, to diverge from each other radially outward from their connection to a maximum opening 16 at the circumference of the casing. The annular zone or space 17 between said compartments constitutes what will hereinafter be termed the smoke space.

Depending from the top wall 9 of the heat-

ing chamber 6 and communicating with the smoke space 17 are vertically disposed smoke conducting flues 18, three being shown in the drawing, which flues also serve as heat distributors with respect to the air within the heating chamber 6. Provided below the respective flues 18 and extending upwardly into the same are burners 19, preferably oil burners of known or suitable construction, which are shown as associated with an oil supply tank 20.

As illustrated, said oil supply tank is held by a shelf 21 which is supported as by means of hanger rods 22 loosely connected to eye attachments 23 of the casing and having hooks or knobs, as 24, which are engageable in slotted ear elements 25 of said shelf. Damper plates 26 are provided for the respective flues 18, said damper plates being located preferably in the smoke space 17 above the respective flues and are arranged to be individually regulated from outside of the casing. 27 represents air down-flow pipes extending from the outer portion of the hot-air reservoir through the smoke space 17 into the heating chamber wherein said down-flow pipes terminate with open ends in proximity of the lower edge of the wall 8.

These pipes are desirably secured by welding or otherwise to the inner surface of the wall 8 thereby serving as ribs to reinforce the wall. The apparatus above described may be supported in any suitable manner—as, for example, by means of legs 28 resting upon the floor or ground and having their upper ends bolted or otherwise secured to lug attachments 29 of the casing. In case it is desired to suspend the apparatus from an overhead support, hangers (not shown) may be employed, the lower ends of which are engaged to the casing attachments 29.

The apparatus may be of any suitable dimensions and constructed of iron or other suitable material. The outer surfaces of the peripheral walls 8 and 10 and of the top wall 12 of the casing may be advantageously provided with a coating of a heat-insulating material.

The lamp burners are lighted for one or more of the flues 18. With the burners thus operating, the smoke resulting from the fuel combustion ascends through the respective flues into the smoke space 17, whence it escapes radially outward into the surrounding atmosphere.

The heat generated at the burners is con-

veyed by the smoke and some air upwardly through the flues subject, however, to the draft control afforded by the dampers 26. The hot combustion products travelling through the flues causes the same to become hot and effect the heating of the air surrounding the flues within the chamber 6; the residual heat discharging into the space 17 is utilized most effectively against the 10 floor 11 of the chamber 7 to heat the air therein.

The air surrounding the flues upon becoming heated ascends through the passages 13 into the central region of the reservoir 15 chamber and thence through the discharge passage 14 into the service pipe 15.

The heated air entering through passage 13 into the reservoir chamber, by reason of the down-flow of air through the pipes 27, 20 tends to be drawn toward the periphery of the chamber 7, some of which air descending through such down-flow pipes into the lower portion of the chamber 6 coating with the upflowing hotter air to create a 25 circulation of air within the interior of the casing. Such circulation of air within the casing and between its chambers 6 and 7 effects a substantially uniform temperature throughout the two chambers 6 and 7 when 30 the discharge from the service pipe is stopped, or nearly so, whereupon the heating chamber 6 acts as a reservoir for hot air supplementary to the chamber 7. The heating surfaces afforded by the flues 18 and the 35 floor of the reservoir chamber 7, taken in connection with the air distribution due to the circulation above referred to, ensures a most economic system of air heating.

The arrangement of the down-flow pipes 40 terminating above the lower edge of the casing, provides a circulatory heating region into which colder air—i. e., air at atmospheric temperature—cannot enter except to progressively replace the heated air as it 45 is withdrawn for use from the apparatus.

The air from below the plane of the lower edge of the wall 8 supplies air to the burners for combustion purposes. The burnt or partly burnt air being carried up the respective flues cannot vitiate the air supply 50 which passes through the hot air reservoir.

While I have illustrated the invention in an embodiment now preferred by me I do not wish to be understood as confining myself thereto as changes may be made within 55 the scope of the following claims.

What I claim, is,—

1. In a heater, the combination with a liquid-fuel reservoir having a plurality of burners, of a casing disposed in spaced relation above said reservoir, said casing being provided with a plurality of substantially horizontal walls dividing the casing into an air-heating chamber, an annular smoke receiving space open to the atmosphere surrounding the casing, and a hot-air chamber disposed successively one above another, smoke flues extending from the respective burners upwardly through said heating chamber and terminating in said space below the floor wall of the hot-air chamber, and damper devices for the respective flues, said hot-air chamber having an air-inlet and an air outlet.

2. In a heater, the combination with a liquid-fuel reservoir having a plurality of burners, of a casing disposed in spaced relation above said reservoir, said casing being provided with a plurality of substantially horizontal walls dividing the casing into an air-heating chamber, a smoke receiving space, and a hot-air chamber disposed successively one above another, flues extending from the respective burners upwardly through said heating chamber and terminating in said space below the floor wall of the hot-air chamber, damper devices for the respective flues, said hot-air chamber having an air-inlet and a plurality of air-outlets, said inlet communicating with the upper portion of the heating chamber, certain of said air-outlets extending downwardly from said hot-air chamber into said heating chamber.

3. A heater comprising a cylindrical casing divided into a bottomless air-heating chamber, a hot-air chamber provided with an air-outlet and having direct communication with the heating chamber, and an annular space between said chambers, said space being open circumferentially of the 95 casing, flues extending downwardly from said annular space into said heating chamber, said flues being adapted to receive burners in their lower ends, and air down-flow pipes extending from the hot-air chamber into the heating chamber and terminating in spaced relation from the lower end of the heating chamber.

Signed at Seattle, Washington, this 16th day of January, 1926.

RICHARD J. GREVSTAD.
